UNITED STATES PATENT OFFICE.

ALVIN C. RASMUSSEN AND CARL G. SCHMID, OF INDIANAPOLIS, INDIANA, ASSIGNEES
TO INSLEY MANUFACTURING COMPANY, OF INDIANAPOLIS, INDIANA, A CORPOR-
ATION OF INDIANA.

HOISTING APPARATUS.

Application filed July 11, 1921. Serial No. 483,704.

To all whom it may concern:

Be it known that we, ALVIN C. RASMUSSEN and CARL G. SCHMID, citizens of the United States, residing at Indianapolis, in the county of Marion and State of Indiana, have invented a new and useful Hoisting Apparatus, of which the following is a specification.

The object of our invention is to produce a simple and efficient device readily adaptable to buildings of different heights and character by means of which construction materials, such for instance, as lumber for forms for concrete, reinforcing steel material in wheel barrows, may be readily carried to a hoisting mechanism and by the hoisting mechanism delivered to, and in some instances upon, the desired floor levels.

The accompanying drawings illustrate our invention. Figure 1 is an elevation of the apparatus, adjacent portions of the building being shown in section; Fig. 2, a plan of the parts shown in Fig. 1; Fig. 3 a front elevation of the hoisting and dumping elements, on a larger scale; Fig. 4, a side elevation of the parts shown in Fig. 3 together with the dumping cam and Fig. 5 a fragmentary plan of the parts shown in Fig. 4.

The primary hoisting and dumping element comprises a pair of platform supporting bars or channels 10, which are supported by a substantially rectangular frame comprising an upper cross bar 11, a lower bar 12, side bars 13 and upwardly extending divergent braces 14, 14 connected at their lower ends to cross bars 12 by a gusset plate 15 and at their upper ends connected to cross bar 11 by gusset plates 16, 16 which also serve to connect the cross bar 11 with side bar 13. The outer ends of bar 10 are supported by diagonal braces 17 which, at their lower ends are connected to side bars 13 by gusset plates 18, and at their upper ends to bars 10 by gusset plates 19.

The upper ends of side bars 13 are connected to the platform supporting bars 10 by gusset plates 20. Each gusset plate 20 carries a laterally projected roller 21 and each bar 10 carries a laterally projected roller 22 parallel with the adjacent roller 21 and spaced therefrom for the purpose which will appear. Each gusset plate 16 carries a roller 23 adjacent rolls 21 and 22

but with its axis at right angles to the axes of rollers 21 and 22.

Each gusset plate 18 carries a laterally projected roller 24 having its axis parallel with the axis of roller 21 and normally in the same vertical plane; and also carries a laterally projected roller 25 having its axis parallel with the axis of roller 24 and normally in the same vertical plane as the axis of roller 22. The lateral spacing between the axes of each pair of rollers 24 and 25 is substantially the same as the lateral spacing between each pair of rollers 21 and 22, but the axis of roller 25 is placed somewhat higher than the axis of roller 24 for the purpose which will appear. 70

The lower ends of side bars 13 are connected to the adjacent ends of cross bars 12 by gusset plates 26 and each of these gusset plates carries a roller 27, the axis of which is parallel with the axis of the companion roller 23 and in the same vertical plane. 75

Gusset plate 15 carries a support 28 to which the lower end of a hoisting cable 29 may be attached. 80

The arrangement of each group of rollers 21, 22, 23 and 24, 25, 27 is such that each group will embrace and connect with three sides of a vertical guide 30 which may be conveniently formed of timber which, in practice, may be formed by successive lengths of 6 x 6 material supported upon a convenient footing and held in vertical position along side of the building by braces 31 which are secured to the outer end side 90 faces of the member so as not to interfere with the free passage of the roller groups. 85

In order to dump the load carried by the platform 33, which is supported by the bars 10, in case automatic dumping is desired, 95 we provide a readily transportable cable stretcher which comprises a light horizontal frame 35, vertical members 36, 36, inclined members 37 and cam track 38 having a downwardly presented mouth 39 which, by 100 proper placing of the frame 35 upon any desired floor of the building, may be brought into alignment to receive the rollers 22.

Sheave 40 for the hoisting cable 29 might 105 be supported permanently upon frame 35 but we find that it is much more convenient to journal the sheave 40 at one end of a

bar or support 41, conveniently formed by a pair of spaced and connected channels of comparatively short length, so that the unit may be readily handled, and adapted to be attached to a timber 42 of sufficient length to extend back upon the flood level to form proper anchorage for the sheave.

The apparatus being primarily designed for handling material of considerable length, such, for instance, as lumber, reinforcement bars, etc., it is desirable that a load be prepared during the period of hoisting and, therefore, we provide a pair of loading devices LL which may be placed so as to flank the foot of the hoisting apparatus as shown in Fig. 2. Each of these loading devices consists of a frame 50 adapted to rest upon the ground and comprising a pair of tracks 51 having a length somewhat greater than twice the width of the platform 33. Upon each pair of tracks is mounted a carriage 52 having a width substantially equal to the width of the platform 33, the arrangement being such that the two carriages 52, 52 when projected beyond the vertical plane of movement of platform 33, as shown in Figs. 1 and 2, will serve for the support of the ends of the material to be hoisted and, after loading, may be shifted along tracks 51 so as to carry the accumulated material into position over the hoisting platform.

The primary hoisting and dumping apparatus, embodying the hoisting platform 33 and its carriers—the cam frame 35 and associated parts; the frames 50, and the carriages 52, 52 and the sheave element 40—41, will be manufactured as individual units so that they may be readily transported, handled and assembled by the contractor.

At a convenient point along side the prospective building, the contractor will provide a pit 60 of sufficient depth to permit the hoisting platform 33 to be lowered to a position slightly below the plane of carriage 52 when frames 50 are set upon the ground adjacent the pit 60, and the guide rails 30 will be erected in place and supported from the frame of the building or from the forms, being extended vertically from time to time as the building grows.

In case of a reinforced concrete structure, the contractor will find it readily feasible to set in the concrete of each floor level, convenient bolts 61 which may be utilized for clamping the cam frame 35 in place.

When the material to be handled, such for instance, as lumber or reinforced rods, may be practically automatically dumped at the desired floor level, the cam frame 35 will be placed in position and when the hoisting platform has neared its upper position, the rollers 22 will be engaged by the cams 38 and the entire platform structure will be

automatically swung to the position showed in dotted lines in Fig. 1, the edge of the platform adjacent the building being brought into conjunction with the upper ends of the inclined members 37 of frame 35, so that the load will be allowed to slide from the hoisting platform onto the inclined members 37 and be there supported so that they may be readily carried away to desired positions.

When automatic dumping is not desired, the sheave structure 40—41 is generally located at a higher level than the floor level to which material is to be delivered, as by wheel barrows, etc., and a receiving platform of planks laid upon the desired floor level and projected so as to properly bridge the gap between the edge of the floor and the adjacent edge of the hoisting platform.

It will be noted that during the lower part of the travel of the hoisting platform, the center of gravity of the structure relative to the hoisting cable is outside the hoisting plane and consequently rollers 22 and 24 will act against the guides 30. When rollers 22 come in contact with the cams 38, rollers 21 will have passed above the upper ends of guides 30 and the entire hoisting platform structure will be swung around the point of contact between rollers 24 and the outer faces of guides 30 until the center of gravity of the loaded structure has nearly reached the vertical plane of its point of pivotal contact. During this movement, rollers 25, because they are initially placed higher than rollers 24, will move away from the inner vertical faces of the guides 30 and then again approach these faces at a point lower than rollers 24.

As the center of gravity of the load passes through the neutral plane, the hoisting platform structure will pivot slightly about the axis of rollers 22 (said rollers being then held in the cam structure), and rollers 25 will come in contact with guides 30. The various parts may be so relatively placed, as indicated in the drawings, that the "kick" as the center of gravity passes through the neutral plane will not have any objectionable effect upon the guides 30.

It will be noticed that by the above described construction the hoisting platform structure is directly pivoted upon the vertical guides 30 and that we have entirely eliminated the usual primary frame slideable upon the vertical guides and serving as a pivotal support for the load-carrying and dumping platform.

We claim as our invention:

1. As an article of manufacture, a hoisting platform provided at its upper and lower ends with laterally projected guide-engaging members, said guide engaging members at the lower end being arranged in pairs, one of each pair being normally at a higher level than the other of said pair, 130

and the members of each pair being laterally spaced for the reception of the guide member between the same.

2. In a hoisting apparatus, the combination of vertical guides, a hoisting platform cooperating with said guides by means of upper and lower guide-engaging members whereby the platform may swing laterally when the upper guide engaging members 10 are carried beyond the vertical guides, a cam structure arranged at the upper end of the vertical guides to engage the hoisting platform and shift the upper end thereof laterally, a hoisting cable connected to the 15 hoisting platform, and a sheave for said hoisting cable arranged below the dumping position, whereby said hoisting platform may be swung by the cam over the sheave.

3. In a hoisting apparatus, the combination of vertical guides, a hoisting platform having a direct swinging interlocking engagement with the guides permitting freedom of longitudinal movement of the hoisting platform upon the guides, means carried by the platform at an upper point normally engaging the guides to hold the upper end of the platform in load carrying position, a cam structure, means carried by the hoisting platform for engaging with the 25 cam structure to swing the hoisting platform laterally to load delivering position, a hoisting cable attached to the lower end of the hoisting platform and a sheave for said hoisting cable, arranged below the load 30 delivering position of the hoisting platform.

4. In a hoisting apparatus, the combination of vertical guides, a hoisting platform provided at its lower end with a pair of laterally and vertically spaced guide-engaging

members for each guide, members at a 40 higher point on the platform engaging said vertical guides and arranged to prevent the tilting of the platform, and a hoisting cable attached to the platform at a point adjacent the lower guide-engaging members. 45

5. A hoisting apparatus comprising a vertically movable and laterally swingable load carrying platform, and a cam structure adapted to be placed at any desired level to engage the platform adjacent its upper end 50 and swing the same laterally to load delivering position, said cam structure embodying inclined portions arranged to receive the load delivered thereto from the platform, when said platform is swung to load deliver- 55 ing position.

6. A hoisting apparatus comprising a load carrying platform provided with guide-engaging members permitting vertical movement of the platform and a swinging load 60 dumping movement of the platform, a cam structure adapted to be placed at any desired level, the cam structure and load carrying platform having inter-engaging members to produce lateral swinging movement 65 of the upper end of the platform, an independent sheave carrying element and a hoisting cable connected to the platform and carried over the sheave element, said sheave element being independent of the cam ele- 70 ment whereby it may be placed either above or below a dumping position platform.

In witness whereof we, ALVIN C. RASMUSSEN and CARL G. SCHMID, have hereunto set our hands at Indianapolis, Indiana.

ALVIN C. RASMUSSEN.
